ABSTRACT

An ink ribbon spool for type-writing machines is disclosed, assembled from two congruent parts. Each part comprises an essentially cylindrical hub portion made of plastics and a metal, disc-like flange anchored to the hub portion by dove-tailed projections directed inward and embedded in the plastics material of the hub. The two spool halves are connected by pins and recesses acting like a snap fastener. The spool disclosed is adaptable to spool drive mechanisms having different dimensions. Universality is achieved by elastic lug-elements integrally attached to the interior wall of the hub portion and serving to center the spool on the driving axle. Preferably a metal strip having the form of a double-headed arrow is inserted between the spool halves and serves as a hook for fastening the end of the ink ribbon.

FIG. 1

FIG. 3

FIG. 4

FIG. 2

**TYPEWRITER RIBBON SPOOL HAVING
CONGRUENT HALVES FORMED OF PLASTIC
AND METAL**

BACKGROUND OF THE INVENTION

This invention relates to an ink ribbon spool for typewriters. Most of such ribbon spools are still made from sheet metal and comprise a hub made from sheet metal rolled substantially to a cylinder which hub is connected to two disc-like flanges serving to guide the ribbon laterally. In most cases, the flanges are connected to the hub by seaming or folding over or by lugs formed on one part and inserted through slots in the other part which lugs are then bent over. Numerous operations are required in the manufacture of such sheet metal parts.

Attempts had been made and are still being made to manufacture such ribbon spools from plastics material. It has been found, however, that particularly the flanges exhibit a certain tendency to deform after the spool has been removed from the mold, and that, in consequence, lateral guidance or even winding and unwinding of the ribbon may be impaired severely.

For such spools made of plastics, embodiments have been proposed manufactured in one piece as well as embodiments assembled from a plurality of separately made parts. In the latter case, a plurality of different molding tools had to be provided for making the several parts. Thus the costs of manufacture of such spools had been considerably increased.

SUMMARY OF THE INVENTION

It is an object of the invention to avoid the disadvantages described above. This is accomplished according to the invention in that the spool is assembled from two spool halves each having a hub portion and a flange, each of the halves having congruent form, the shell of each hub portion extending to the mid-line of the ink ribbon to be wound onto the spool and in that each hub portion is made from plastics material and the flange is made from sheet metal, being embedded into the hub portion by molding.

According to another feature of the invention, each flange comprises dovetail-shaped projections directed radially inward for being embedded in and anchored to the hub portion. According to another feature of the invention for connecting the spool halves each hub portion is provided with at least one pin arranged parallel to the spool axis and protruding over the partition face between the spool halves and with corresponding recesses equal in number to that of the pins, the pins and the recesses being arranged eccentric to the spool axis.

Preferably, each hub portion is provided with a slot parallel and eccentric to the spool axis into which a strip of sheet metal is insertable, the strip of sheet metal having the shape of a double arrow whose arrow-heads protrude over the shell of the hub portion and serve to fasten the end of the ink ribbon, and wherein additionally each hub portion adjacent to the slot is provided with a recess arranged parallel to the spool axis into each of which recesses a sleeve is insertable, the sleeves being integrally attached to the sheet metal strip and consisting of rolled lateral projections thereof.

BRIEF DESCRIPTION OF THE DRAWING

A number of further desirable features of the invention will be explained with reference to the drawing, in which:

FIG. 1 is a top plan view showing one spool half as viewed from the associated other spool half,

FIG. 2 shows a spool which has been assembled from two halves, one of which is shown in a section taken 10 along line 2-2 in FIG. 1,

FIG. 3 shows a metal strip which has the shape of a double arrow and is provided with fixing hooks, and

FIG. 4 shows the metal strip in an elevation at right angles to FIG. 3.

**DESCRIPTION OF THE PREFERRED
EMBODIMENTS**

The spool 1 consists of two identical spool halves 1a and 1b. Each spool half 1a, 1b consists of a cylindrical hub portion 2 (a or b) of plastics material and a disc-like flange 3 (a or b) of sheet metal. The flange 3 is held in the hub portion 2 by means of dovetail-shaped projections 23 protruding radially inward, which projections 23 are embedded in the hub portion 2 by molding. 20 Hereinafter, where it appears necessary for the sake of clearness, reference characters are provided with the suffixes *a* or *b* to indicate that the designated component belongs to a specific spool half 1a, 1b for instance, the left-hand spool half 1a in FIG. 2, or the other spool half, such as the right-hand spool half 1b. Attention is directed to the fact that there is basically no difference between components having reference characters which differ by the suffixes *a* and *b* only, and that such components are identical or congruent components of congruent spool halves 1a, 1b.

Each hub portion 2 consists of an end wall 20 and an approximately cylindrical casing 9. The height of the cylinder is approximately one half of the width of the ink ribbon. The end wall 20 is provided with radially elongated apertures 21, which at the center of the end wall 20 merge into a circular aperture 24 and together with the latter form a coupling star, which is adapted to receive the axis of a spool holder and one or more coupling pins of a spool drive. This spool drive is not shown in the drawing.

From the inner surface of the cylindrical casing 9 of the hub portion 2 made of plastic spring lugs 22 which are integrally molded to the casing 9 extend first radially inward and are angled in the same direction each where they are adjacent to the circular aperture 24. In their radial portion, these spring lugs 22 in part are firmly connected to the end wall 20. Just as the apertures 21, spring lugs 22 are arranged in a centrally symmetrical pattern. They serve to center the spool 1 on the spool axle. The cylindrical casing 9 of the hub portion 2 is increased in thickness at two diametrically opposite sections. One of the thickened portions has a preferably oval recess 5 arranged parallel to the axis of the spool 1, and beside said recess 5 has a pin 4, which is also parallel to the axis of the spool 1 and protrudes over the jointing plane of the hub portion 2. The pins 4 and recesses 5 of two identical spool halves 1a, 1b are so designed that each pin 4a can be inserted into a recess 5a and each pin 4b can be inserted into a recess 5b so as to form a permanent joint. The recesses 5a, 5b may be slightly undercut and the pins 4 may be somewhat thickened at their tip so that a joint is obtained

similar to that of a snap fastener. Pins 4 and recesses 5 are arranged eccentric to the axis of spool 1.

The recesses 5 do not extend through the entire hub portion 2 but extend only to a point adjacent to the end wall 20. The connecting pins 4 are correspondingly shorter. To enable air to escape from the recesses 5 as the pins 4 are forced into the same, the recess 5 is continued by a venting opening 25 in the end wall 20.

The other, thickened portion of the hub casing 9, diametrically opposite to the connecting pins 4 and recesses 5 has a slot 6 (a or b) which extends along a chord of the circle representing the cylindrical casing 9, which slot 6 intersects the thickened portion of the hub portion 2 approximately parallel to the spool axis. In each spool half 1a, 1b two cylindrical recesses or apertures 10, 11(a or b) approximately tangentially adjoin said slot 6. A metal strip 7 having the shape of a double arrow and provided with arrow-heads 8 can be inserted into the slot 6 so that the arrow-heads 8 protrude over the periphery or casing 9 of the hub portion 2 of the spool 1. The two arrow-heads 8 are angularly bent toward the hub portion 2 of the spool 1 to form a fixing hook to which the end of the ink ribbon is secured. In a preferred embodiment of the metal strip 7, two punched projections are provided on each side, which projections are equally spaced from the middle of the double arrow and which during manufacture of the double arrow are rolled to form sleeve portions (12, 13, 14, 15) insertable into the apertures 10 a, b and 11 a, b. Because the apertures 10 and 11 are symmetrical with reference to the same plane of symmetry as the connecting pin 4 and the corresponding recess 5, the sleeve portions 12, 13, 14 and 15 of the metal strip 7 can be inserted simultaneously into the apertures 10a, 11b and 11a, 10b so as to contribute to a permanent connection of the two spool halves 1a and 1b.

The spool 1 shown and described can be made at very low cost as a mass-produced article. A single mold is sufficient to make the spool halves 1a and 1b. The flange 3 made of sheet metal is inserted into the mold, which is then closed, and plastics material is injected into the mold to make the hub portion 2. A metal strip 7 is inserted into two spool halves 1a, 1b and the hub portions 2 of the latter are superimposed so that each pin 4 can enter an opposite recess 5 of the other hub 45

portion 2. After the two hub portions 2 have been forced together, the spool 1 is ready to receive a ribbon.

I claim:

5. 1. In an ink ribbon spool comprising two spool halves, each spool half including a hub portion and a flange, wherein the two spool halves have congruent form, a casing of each hub portion extending to a midline of an ink ribbon to be wound onto the spool, each hub portion being made from plastic material, the improvement wherein each flange is made of sheet metal and has dovetail shaped projections directed radially inward for being embedded in and anchored to the hub portion; each hub portion being provided with at least 10 one pin arranged parallel to the spool axis and protruding over the jointing plane of the spool halves, and with first recesses corresponding to the pins and equal in number; the pins and the first recesses being arranged eccentrically to an axis of the spool; and the spool 15 halves being connected at the hub portions by fitting the pins into the first recesses.

2. An ink ribbon spool according to claim 1, wherein each hub portion is provided with a slot parallel and eccentric to the spool axis and into which a strip of sheet 25 metal is inserted, the strip of sheet metal having the shape of a double arrow having arrowheads which protrude over the casing of the hub portion and serve to fasten an end of the ink ribbon, a plurality of sleeves integrally attached to the sheet metal strip and consisting of rolled lateral projections thereof and wherein additionally each hub portion adjacent to the slot is provided with a further recess arranged parallel to the spool axis into each of which further recesses a respective sleeve is insertable.

3. An ink ribbon spool according to claim 2, wherein each hub portion has two of the first recesses positioned symmetrically with reference to a plane of symmetry governing the positions of said pins and first recesses.

4. An ink ribbon spool according to claim 1, wherein each hub portion has two of the first recesses positioned symmetrically with reference to a plane of symmetry governing the positions of said pins and first recesses.
